UNITED STATES PATENT OFFICE.

WOLCOTT J. PARMELEE, OF WILKES-BARRÉ, PENNSYLVANIA.

MACHINE FOR ROLLING AXLES.

SPECIFICATION forming part of Letters Patent No. 444,253, dated January 6, 1891.

Application filed August 22, 1890. Serial No. 362,761. (No model.)

To all whom it may concern:

Be it known that I, WOLCOTT J. PARMELEE, a citizen of the United States, residing at Wilkes-Barré, in the county of Luzerne and 5 State of Pennsylvania, have invented a new and useful Process of and Apparatus for Rolling Axles, of which the following is a specification.

This invention relates to the manufacture 10 of vehicle-axles by rolling the spindles upon the same, instead of forging them under the hammer, as has been formerly done.

The invention consists in the improved 15 process and apparatus which will be herein-after fully described, and particularly pointed out in the claims.

In the drawings, Figure 1 is a side elevation of a set of rolls having dies to operate in accordance with my invention. Fig. 2 is a 20 vertical sectional view of the same.

Like numerals of reference indicate like parts in all the figures.

The rolls, which are designated by 1, are 25 suitably geared together and are provided with longitudinal ribs 2, upon which the dies 3 and 4 are mounted. Said dies are provided in their faces, which are concentric to the axis of the rolls, with grooves 5 and 6. The grooves 5 in the dies 3 are semi-elliptical in 30 contour, while the grooves 6 in the dies 4 are semicircular. The dies 3 may be designated as the "shaping-dies," while the dies 4 are the "finishing-dies."

It is obvious that the grooves in both the 35 shaping and the finishing dies are to be made tapering from end to end, so as to produce the requisite taper in the spindles which are to be formed therein.

In practice the blank, which is a bar of 40 square iron of suitable dimensions, is heated to the requisite degree, and is then fed by the operator between the dies 3 of the rolls, which are caused to revolve by suitable motive power. The said dies 3 will impart to the 45 end of the blank an elliptical and tapering shape. The dies, it will be observed, extend only part way around the circumference of the rolls. Hence the blank, after passing between and being operated upon by the faces 50 of the dies, will be released by the latter, and may be readily withdrawn from the rolls without passing between the latter. The blank-

bar is then, after being withdrawn from the rolls, reversed to the extent of one-quarter revolution and again fed between the dies 3. 55 The effect of this second manipulation will be that the spindle is upset and its elliptical shape changed to one which more nearly approximates the circular. Having undergone this second manipulation, the spindle end of 60 the blank is passed between the finishing-dies 4, from which it receives the tapering and in cross-section the true circular shape. The blank is then ready for subsequent manipulations to form the collar, after which it is 65 trimmed in the usual manner by turning and otherwise.

By my invention a single set of rolls having suitably-constructed dies will be sufficient to shape the spindle of the axle, which has 70 heretofore been done exclusively by hammer-forging in a comparatively slow and expensive manner. I also desire to state that, while by the process of hammer-forging reheating of the axle is necessary to fit it for subsequent 75 operations, my improved process of rolling the spindle is so rapidly performed as to render reheating unnecessary.

Having thus described my invention, what I claim, and desire to secure by Letters Patent 80 of the United States, is—

1. In the manufacture of vehicle-axles, the process of forming the spindle by rolling, which consists in first compressing the end of the axle-blank to a tapering shape elliptical 85 in cross-section, next upsetting the tapering elliptical portion by edgewise pressure to an approximate circular shape in cross-section, and finally finishing between tapering roller-dies circular in cross-section, substantially as 90 set forth.

2. In the manufacture of vehicle-axles, the process of forming the tapering spindle by rolling, which consists in subjecting the blank to the action of revolving dies acting from 95 the point in an inward direction, the blank being withdrawn from between the rolls after each operation of the dies, substantially as set forth.

3. In a machine for forming spindles upon 100 axle-blanks, the combination, with the rolls, of the spindle-shaping dies mounted detachably upon the same, substantially as set forth.

4. The combination, with the rolls, of the

spindle-shaping dies mounted detachably upon and extending part way around said rolls, substantially as set forth.

5. The rolls having longitudinal ribs, in combination with the dies mounted thereon, extending part way around the rolls and having tapering recesses respectively semi-elliptical and semicircular in cross-section, substantially as and for the purpose set forth.

In testimony that I claim the foregoing as my own I have hereto affixed my signature in presence of two witnesses.

WOLCOTT J. PARMELEE.
